UNITED STATES PATENT OFFICE

1,959,082

MATTRESS AND ITS MANUFACTURE

Charles Lofman, Riverside, Ill., assignor to S. Karpen & Bros., Chicago, Ill., a corporation of West Virginia

Application December 15, 1930, Serial No. 502,533

7 Claims. (Cl. 5—360)

This invention relates particularly to mattresses or the like, in which the filling within the mattress-casing comprises a body of springs suitably connected together to afford an inner spring-structure, and suitable loose filling material, such as hair, cotton or the like, which supplements the spring-structure and completes the filling of the mattress.

The primary object is to provide an improved method of manufacture, which enables a superior product to be produced at a very moderate cost. A further object is the production of such improved product.

In accordance with the present invention, a suitable spring-structure, comprising a body of light upholstery springs suitably connected together, is provided; a pre-built border-boxing (preferably quilted and comprising inner and outer fabrics and interposed filling material) and marginal inner edge-rolls are then tied or stitched to the marginal portion of the spring-structure at the planes of the upper and lower surfaces thereof; loose, or felted filling or stuffing material is then placed over the sides of the spring-structure and may be reflected over the inner edge-rolls; and the upper and lower casing-fabrics are then placed in position and sewed to the upper and lower marginal portions of the border-boxing, it being understood that these portions project above and below, respectively, the upper and lower surfaces of the spring-structure.

The method thus stated renders it possible to provide the mattress, or cushion, with edge-rolls in an extremely simple and effective manner. That is, one can in this manner produce a half-roll edge which gives an exceedingly pleasing appearance and effect, coupled with the highest utility.

The invention is illustrated in preferred embodiments in the accompanying drawings, in which—

Fig. 1 is a broken elevational view of one form of quilted border-boxing; Fig. 2, a similar view of a slightly modified form of border-boxing; Fig. 3, a vertical sectional view taken as indicated at line 3 of Fig. 1; Fig. 4, a broken horizontal sectional view taken as indicated at line 4 of Fig. 1; Fig. 5, a broken elevational view of the improved mattress employing the border-boxing illustrated in Fig. 1; Fig. 6, a broken vertical sectional view of the mattress shown in Fig. 5; Fig. 7, a broken detailed sectional view showing a slight modification in the attachment of the inner edge-roll to the spring-structure and boxing; Fig. 8, a broken plan view of a modified form of mattress, in which the inner edge-roll is positioned somewhat dif-

ferently than in the preceding structures; Fig. 9, a broken vertical sectional view of the structure shown in Fig. 8, the upper layer of filling and the upper casing-fabric being omitted; Fig. 10, a broken elevational view of the mattress shown in Fig. 8, it being noted that the border-boxing of Fig. 2 is here employed; and Fig. 11, a broken elevational view showing the mattress constructed with still another modification of the border-boxing.

In the construction illustrated in Figs. 1 and 3-7, the mattress comprises a border-boxing A; a spring-structure B; inner edge-rolls C; ties or stitches D which unite the edge-rolls and the boxing to the spring-structure; layers of filling material E, which are placed over (above and below) the spring-structure after the border-boxing and edge-rolls have been secured to the marginal rows of springs of said structure; and horizontal casing-fabrics F constituting the upper and lower sheets of the casing.

The border-boxing A preferably is quilted in any suitable manner. Preferably, the boxing comprises an outer strip of casing fabric 1, an inner strip of muslin 2, and an interposed layer 3 of filling, such as cotton.

In the illustration given in Figs. 1 and 3-6, the quilting is effected by sewing the fabrics and interposed filling material together along the longitudinal lines 4 at a distance of an inch more or less from the edges, and also sewing the parts together by oval lines of stitching in the vertical plane, as indicated at 5, the ends or apices of the ovals meeting the longitudinal lines of stitches at the points 6.

The spring-structure B may be formed in any suitable manner. Preferably, a body of light upholstery springs are set together in longitudinal and transverse rows and are suitably connected together. In the illustration given, a body of springs of the Marshall type is shown. In this type of spring-structure, the upholstery springs 7 are inclosed in fabric pockets, or fabric cells 8, and the springs are united together by ties, or strings 9.

In forming a mattress in accordance with the present invention, a workman takes a body of springs and stitches to one marginal portion of the spring-structure the boxing A and an edge-roll C. The stitching is continued above the body of springs until the border has been secured to the spring-structure throughout the periphery thereof. The operation is repeated at the other corner of the spring-structure. In the illustration given, the ties D may be understood as stitch-

ings of string performed by means of a darning-needle.

When the operation just described has been completed, the structure comprises the spring-structure, the edge-rolls, and the border-boxing 5 properly united together.

In the illustration given, a layer of cotton or the like 10 is placed adjacent the marginal row of springs before the border-boxing is applied.

10 The ties or stitchings D preferably extend wholly through the boxing and at the points where the stitching is exposed, the loops register with the apices of the ovals 5. That is, they register with the points 6, where the apices of 15 the ovals register with the horizontal lines of stitchings 4.

After the boxing and edge-rolls have been applied to the spring-structure, the workman places the layer of filling material E upon the spring-structure, places a fabric F thereover, and then, 20 by means of a sewing machine, sews the edge-portion of the fabric F to the upper edge portion of the fabric 1 of the boxing, as indicated at 11. In forming the seam at 11, a binding tape 12 is 25 preferably folded over the edges of the fabric and sewed into the seam.

Having completed the mattress at one side, the structure is reversed, the filling E is applied over the spring-structure, the other horizontal casing-fabric F is applied and the fabrics are united 30 at the corner seam 11.

By reference to Fig. 3, it will now be understood that the effect of the method described is to produce at the border-boxing inwardly drawn 35 lines 4 which extend completely about the mattress periphery, as indicated in Fig. 5. However, the upper and lower surfaces of the mattress are not drawn downwardly or inwardly near the edges, so that the result is to leave the upper 40 and lower casing-fabrics substantially smooth near the margins, and simply rounded over to meet the seam 11, as indicated at 14. Thus, something approaching a pin-cushion effect and involving a half edge-roll effect is produced. The 45 result is an exceedingly pleasing appearance, coupled with a luxurious edge effect for the mattress.

In Fig. 7, a method of applying the inner edge-roll C is shown in some detail. A thick strip of 50 cotton, or a thick strip of curled hair (having cheese-cloth secured to it, if desired) is employed. This strip may be connected with the boxing and with the spring-structure by means of the ties D, as shown in Fig. 7. That is, the stitchings 55 may pass through the central portion of the strip, and the strip may ultimately be filled, so as to form a row when the casing-fabrics are to be united at the corner seam of the mattress. It will be understood that the illustrations are 60 more or less schematic, it being difficult to reproduce the exact structure after it has been completed. Moreover, the details may be varied.

In the modification shown in Figs. 2 and 8-10, the structure is similar to that already described, 65 and parts are correspondingly designated, except that the modified border-boxing is designated A' and the modified edge-roll is designated C'. In this construction, the quilting of the border-boxing is similar to that already described, except 70 that the oval ends of the vertical figures designated 5^a are formed by vertical lines of stitching and the figures are completed by inclined straight lines of stitching which form angles 5^b. The boxing has the horizontal lines of stitching 4, the 75 same as previously described.

As illustrated in Figs. 8 and 9, the edge-roll C' comprises a roll of hair 15 attached to or enclosed in a strip of cheese-cloth 15^a. In this example, a portion of the roll is interposed between the spring-structure B and the border-boxing 80 A'. The parts are united by ties or stitchings D', as appears in Figs. 9 and 10.

In the modification shown in Fig. 11, the structure is substantially like the previously described constructions, and corresponding parts are correspondingly lettered. In this instance, the border-boxing is designated A², being slightly modified. 85

The edge-roll is designated C². The boxing A² is quilted by means of horizontal lines of stitching 4^a and vertical lines of stitching 4^b, thus producing rectangular vertical figures between the planes of the horizontal lines of stitching 4^a. The vertical lines of stitching produce rudimentary vertical flutings between the lines of horizontal stitching. 90

The roll C² is shown as comprising a hair roll. The filling material above the spring-structure, designated E², is shown as comprising inner and outer layers of cotton or kapok 16 and an intermediate layer of curled hair 17. An exceedingly luxurious effect and an extremely pleasing appearance is secured in this construction. The ties or stiches D² connect the boxing A² with the edge-roll C² and with the spring-structure in 105 the manner described with reference to the previously described constructions. 100

In this instance, the short exposed loops of the ties D² register with the intersections of the vertical lines of stitching 4^b with the horizontal lines 110 of stitchings 4^a.

From the description given, it will be understood that the improved method obviates the necessity of carrying the ties or stiches which form the edge-roll of the mattress through the 115 layers of filling material above the springs and through the horizontal casing-fabric. The effect is to simplify the manufacture and improve the appearance.

The foregoing detailed description has been 120 given for clearness of understanding only and no unnecessary limitations should be understood therefrom, but the appended claims should be construed as broadly as permissible in view of the prior art. 125

What I regard as new, and desire to secure by Letters Patent, is:

1. A method of manufacturing a mattress with half-roll edge effect, which comprises: employing as a filling a spring-structure which comprises 130 marginal rows of light gauge upholstery springs; stitching an internal edge-roll and a quilted boxing to the marginal rows by a common stitching at the plane of one surface of the spring-structure, said stitching being adapted to give a half-roll edge effect at the boxing and the edge-portion of said boxing projecting a distance above said surface of the spring-structure; applying a layer of filling material over the spring-structure; and applying a casing-fabric over said layer and sewing its edge-portions to the corresponding edge-portion of the boxing. 135

2. The method of mattress manufacture specified in claim 1 as carried out by introducing a portion of the edge-roll between the boxing and the marginal row of springs and simultaneously stitching the boxing and the edge-roll to the springs. 145

3. A method of manufacturing a mattress with roll-edge effect which comprises: forming a 150

- quilted border-boxing having horizontal lines of stitching some distance from its edges and having vertical stitched figures intersecting at their ends the horizontal lines of stitchings; stitching 5 by a common stitching the pre-formed border-boxing and an edge-roll to the marginal rows of a body of coil springs serving as a mattress therein, said stitchings passing wholly through the border-boxing and registering at their exposed 10 loops with the points of intersection between the vertical stitchings and the horizontal stitchings of the border-boxing; applying a layer of filling material over the springs; and applying a casing-fabric over said layer of material and sewing 15 the edge-portions thereof to the edge-portions of the boxing. 20
4. In a mattress structure: a body of coiled springs adapted to serve as a mattress filling; a quilted, pre-built border-boxing adjacent the 25 marginal rows of springs; internal edge-rolls at the junctions between the border-boxing and the marginal rows of springs; and common ties connecting the border-boxing and the border rows of springs to the internal edge-rolls, said ties adapted to give a half-edge roll effect to the border-boxing. 30
5. A structure as specified in claim 4, in combination with layers of filling material above and 35
- below the body of springs and casing-fabrics over said layers and having their edge-portions sewed to the edges of the border-boxing, said casing fabrics presenting smooth unbroken surfaces with pin-cushion effect at the horizontal corner-lines of the mattress. 40
6. A structure as specified in claim 4, in which the border-boxing has horizontal rows of stitchings disposed near its edges and vertical stitchings joining the horizontal rows of stitches, and in which the ties connecting the border-boxing, the springs and the edge-rolls have exposed loops registering with the junctions between said horizontal rows of stitches and the vertical rows of 45 stitches. 50
7. A method of manufacturing a mattress with half-roll-edge effect, which comprises: employing as a filling a spring-structure having marginal rows of light gauge upholstery springs; introducing an edge-roll having a portion thereof between the boxing and the marginal row of springs; simultaneously stitching said edge-roll and the boxing to the springs; applying a layer of filling material over the spring-structure; and applying a casing-fabric over said layer and sewing its edge-portions to the corresponding edge-portion of the boxing. 55
